END FITTING FOR SUSPENDERS

Floyd A. Knoll, Buffalo, N. Y., assignor to Condor Products, Inc., Buffalo, N. Y.

Application December 5, 1936, Serial No. 114,402

4 Claims. (Cl. 241—27)

This invention relates to end fittings for suspenders or other articles by means of which tabs or button straps are secured to another strap.

One of the objects of this invention is to provide a fitting of this kind of improved construction by means of which a plurality of button straps or tabs may be pivotally connected to swing independently of each other relatively to another strap. Another object of the invention is to provide a fitting of this kind of simple, compact and strong construction. A further object of the invention is to provide a fitting of this kind in which a cover or finishing member is provided which is secured to the fitting in such a manner as to hold itself and other parts of the fitting in correct relation to each other. Other objects of the invention will appear from the following description and claims.

In the accompanying drawing:

20 Fig. 1 is a face view of a fitting embodying this invention showing the same applied to suspenders for securing tabs to a suspender strap.

Fig. 2 is a perspective view of a frame or shackle member of the fitting, on an enlarged scale.

25 Fig. 3 is a face view of the frame or shackle member having tabs pivoted thereto.

Fig. 4 is a perspective view of a ball or loop forming a connection between the frame or shackle member and the strap.

30 Fig. 5 is a section, on line 5—5, Fig. 3.

Fig. 6 is a perspective view of a finishing or covering member of the fitting.

Fig. 7 is a sectional view of the fitting, on line 35 7—7, Fig. 9.

Fig. 8 is a section thereof, on line 8—8, Fig. 7.

Fig. 9 is a side view of the fitting.

Fig. 10 is a section thereof, on line 10—10, 40 Fig. 7.

Fig. 11 is a fragmentary section, on line 11—11, Fig. 9.

In the particular embodiment of the invention illustrated in the drawing, 14 represents tabs or button straps of the suspenders and 15 represents suspender straps to which the tabs 14 are connected by means of a fitting embodying this invention.

The fitting includes a frame or shackle member 16 to which the tabs 14 are secured and which is preferably made of sheet metal bent into approximately U-shape and having front and back sides or panels 17 and 18 connected by a transverse integral part 19. The tabs or button straps 14 are arranged with their upper ends 50 extending between the panels or parts 17 and 18 and are secured thereto in any suitable manner. Preferably the tabs are pivotally connected with the shackle by means of a pivot member 20 of any suitable form extending through 55 the tabs and the opposite panels 17 and 18. In

the particular construction illustrated, this pivot member is in the form of a rivet, the opposite ends of which are headed to secure them to the opposite panels or sides of the shackle and to confine these sides and the upper ends of the 5 suspender tabs in correct relation to each other as well as permitting the tabs to swing independently of each other relatively to the frame or shackle.

The tabs or button straps 14 may be of any 10 suitable material or combination of materials to cooperate with the pivot member of the frame or shackle, it having, for example, been found satisfactory to make these tabs of a tough grade of leather in which case the tabs require no metal 15 or other reinforcing parts at their pivoted ends to cooperate with the pivot member. It is not intended, however, to restrict this invention to the particular type of tabs or button straps shown.

20 In order to form a connection between the frame or shackle member 16 and the suspender strap 15, a loop or bail is employed which has a transverse portion or bar 24 around which the suspender strap 15 may be passed or to which the strap may be secured in any suitable or desired manner, and which has a part or parts which may be secured or connected in any suitable manner to the frame or shackle member 16. In the particular construction shown, the bail or loop is provided at the ends of the bar 24 with turned-over hook-like parts 25 adapted to extend between the panels or sides 17 and 18 of the shackle and to engage the connecting cross part 19 thereof. The hook-shaped ends 30 may be enlarged or widened, as shown at 26, to provide an extended bearing surface on the inner face of the connecting part 19 of the shackle. The bail or loop may be readily applied to the frame or shackle 16 turning the bail through 35 about 90° from its intended position and then passing the inner ends of the hook-shaped parts 25 between the two panels or sides 17 and 18 of the frame or shackle and then turning the bail or loop into the position shown in Figs. 1 40 and 7 to 9.

45 After the bail or loop has thus been assembled on the frame or shackle, it is desirable to provide means for preventing the bail or loop from moving in the reverse direction out of engagement 50 with the frame or shackle. Any suitable means extending across the space between the upper parts of the two side panels 17 and 18 may be employed for this purpose. In the particular construction shown in the drawing, I have provided a separate part, which serves the double function of forming a facing or finishing member for the fitting and also of holding the bail or loop in operative relation to the frame or shackle. This finishing member may, of course, be of any 55 60

suitable form or design and may be ornamented, polished, or otherwise finished to improve the appearance of the fitting and to conceal the rivet or pivot member of the frame or shackle. In the 5 construction shown, this finishing member includes a front face or panel 30 which may be of suitable shape to cover all or a part of the front side 17 of the shackle, and preferably, the finishing member also has a flange 31 extending over 10 at least a part of the connecting member 19 of the shackle. The finishing member preferably also is provided with flanges or projections 32 at opposite sides thereof which are spaced from the flange 31 to provide clearance for the bail or 15 loop when the finishing member is slid rearwardly into operative relation to the frame or shackle 16. These side flanges 32 or at least portions thereof are formed to extend inwardly into the space between the two panels or sides 17 20 and 18 of the frame or shackle, which may be done by pressing the side flanges 32 or portions thereof inwardly between the edge portions of the sides of the shackle. For example, the side flanges 32 may be provided with corner portions 25 33 which may be bent inwardly to engage in rear of the side 17 of the shackle as clearly shown in Fig. 9. The flanges 32 may be beaded or curled inwardly around the edges of the panel or side 17 of the shackle as shown at 34, while 30 the remaining portions of the flanges extend across the open space between the edges of the sides 17 and 18 of the shackle to retain the bail in place and to provide a more finished appearance of the fitting. The inwardly bent or beaded 35 portions of the flanges may be formed thereon after the finishing member has been positioned on the shackle or they may be formed thereon before such assembly, in which case the flanges of the finishing member may be forced or snapped into final position on the shackle. Either or 40 both of these expedients may be employed or other means for retaining the bail or loop in its operative position may be used. The flanges 32 prevent the finishing member from again being slid forwardly out of operative relation to 45 the frame or shackle and the flange 31 prevents the finishing member from being moved downwardly out of its operative position. The flanges of the finishing member, consequently, serve to firmly secure the finishing member on the 50 frame or shackle and also hold the bail or loop in its operative position by preventing the same from being moved downwardly out of engagement with the shackle member. The front panel 30 as well as the flanges 31 and 32 also give the 55 fitting a finished appearance and such finished appearance will not be damaged or changed by the pressing in of the side flanges 32, which in turn partly close the sides of the shackle and thus improve the appearance thereof. It is, of course, 60 not necessary that all of the sides extend inwardly into the sides of the U-shaped shackle, since it is sufficient if only parts of these flanges are bent inwardly to grip the edges of the front or rear panel or part of the shackle.

65 The construction described results in a fitting which is strong and rigid and yet of small size and compact, particularly in that the transverse dimension of the fitting is very little more than the combined thickness of the tabs or button straps supported thereby. While two of these

tabs are shown, it will be obvious that the fitting will operate equally well, if additional tabs are pivoted thereon. By means of the construction described, the frame or shackle member may be made of any suitable material and any deformation of the same due to riveting or other operations will be entirely concealed by means of the finishing member. 5

I claim as my invention:

1. A fitting for supporting a plurality of tabs 10 from a strap, including a shackle having spaced sides between which ends of said tabs extend, means for connecting said tabs to said shackle, a loop to which said strap may be secured and having end portions extending into engagement 15 with said shackle between the sides thereof, and a finishing member extending across a side of said shackle and having parts extending between said sides for securing said loop to said shackle 20 and for securing said member to said shackle. 20

2. A fitting for supporting a plurality of tabs from a strap including a shackle of substantially U-shape having sides between which the ends of the tabs extend and having a part connecting the sides of the shackle, means for securing said ends of the tabs to said shackle, a loop to which said strap may be secured and which has parts extending between the sides of the U-shaped shackle and engaging said connecting part of the shackle, and a finishing member 30 extending across a side of said shackle and engaging said connecting part of the shackle, said finishing member having parts extending crosswise of the space between said sides adjacent to said loop and engaging edge portions of a 35 side of the shackle to hold said finishing member in place on said shackle and to hold said loop in its operative position.

3. A fitting for supporting a plurality of tabs from a strap including a shackle formed of a 40 sheet of metal bent into substantially U-shape to form spaced sides and a part connecting said sides, means for securing the ends of tabs between said sides, a loop to which said strap may be secured and having ends bent inwardly toward each other and extending between the sides of said shackle and engaging the connecting part thereof, and a finishing member secured to a side of said shackle and having flanges extending across the space between said sides for holding 45 said loop in its operative position on said shackle. 50

4. A fitting for supporting tabs from a strap, including a shackle of substantially U-shape and having sides connected by an integral part, means for securing said tabs between said sides, 55 a loop to which said strap may be secured and having end portions bent toward each other and extending between said sides of the shackle and engaging said connecting part, and a finishing member having a panel extending across a side 60 of said shackle and a flange extending across said connecting part of said shackle, said finishing member also having flanges at opposite sides extending across a portion of the space between said sides adjacent to said loop for holding said loop in its operative position on said shackle, portions of said flanges being pressed into engagement with an edge of said side of said shackle to secure said finishing member in operative relation to said fitting. 65
